[57] CLAIM

The ornamental design for an egg cooker, as shown and described.

DESCRIPTION

FIG. 1 is a front perspective view of an egg cooker showing my new design;

FIG. 2 is a rear perspective thereof;

FIG. 3 is a right side elevational view thereof;

FIG. 4 is a left side elevational view thereof;

FIG. 5 is a top plan view thereof;

FIG. 6 is a front elevational view thereof;

FIG. 7 is a rear elevational view thereof;

FIG. 8 is a bottom plan view thereof; and

FIG. 9 is a front perspective view of an egg cooker showing a modification of my new design with a transparent lid and poached egg trays.

*Fig. 1**Fig. 2**Fig. 3**Fig. 4**Fig. 5**Fig. 6*

*Fig. 6**Fig. 7**Fig. 9*
